UNITED STATES PATENT OFFICE.

FRANK W. HESS, OF CHICAGO, ILLINOIS.

DEVICE FOR CLEANING, SCOURING, AND COOLING GRAIN.

SPECIFICATION forming part of Letters Patent No. 746,508, dated December 8, 1903.

Application filed May 11, 1903. Serial No. 156,716. (No model.)

To all whom it may concern:

Be it known that I, FRANK W. HESS, a citizen of the United States, residing at Chicago, in the county of Cook and State of Illinois, have invented certain new and useful Improvements in Devices for Cleaning, Scouring, and Cooling Grain; and I do hereby declare the following to be a full, clear, and exact description of the invention, such as will enable others skilled in the art to which it appertains to make and use the same.

My invention relates to a novel construction in a spout for cleaning, scouring, and cooling grain, the object being to provide a simple and efficient device of this character; and it consists in the features of construction and combinations of parts hereinafter fully described and claimed.

In the accompanying drawings, illustrating my invention, Figure 1 is a side elevation of a grain-spout for cleaning, scouring, and cooling grain constructed in accordance with my invention. Fig. 2 is a vertical longitudinal section of same. Fig. 3 is a transverse section on the line 3-3 of Fig. 2. Figs. 4 and 5 are detail sections showing modified forms of walls for the spout.

My said device consists of a trough or spout A, adapted to be connected with the outlet end of the bin or hopper of an elevator to conduct the grain to a car or vessel for shipment, said spout or trough being preferably of considerable length. The said spout is rectangular in cross-section, its four walls B being composed of wire-cloth of a mesh sufficiently small to prevent passage of the grain therethrough, but made of heavy wire, so as to present a very rough surface to the grain. For certain kinds of grain I prefer to have said wire-cloth made of a heavy square wire, so as to present sharp cutting edges to the grain to scour the same. The mesh and character of the wire-cloth must also be varied according to the character of the grain handled. In the side walls of said spout A are a plurality of slots C, extending the entire width of said walls and at an angle of about fifteen degrees to the top and bottom walls. Said slots C in one of said side walls are in horizontal alinement with the slots in the other thereof, and in said slots I insert screens which are supported in said slots, each con-

sisting of two plates D and E of wire-cloth, the plate D being of small mesh to prevent passage of the grain therethrough and the plate E of very large mesh, so as to permit the grain to readily pass therethrough, said plate D being arranged to lie with its upper edge in contact with the bottom wall of the spout A, and said plate E occupying the space between the lower edge of said plate D and the upper wall of the spout. In said upper wall of said spout A above the lower ends of said plates E, I provide openings controlled by gates F, through which straw, sticks, and nails or other rubbish found in grain and which is caught by said plates E is removed. The said spout is generally set at an angle of from forty-five degrees to an almost vertical position, and the grain in passing through the same is thoroughly scoured by the rough surfaces over which it passes and by its passage over the plates D and through the perforations in the plates E is continually revolved and agitated, such agitation serving to expel the dust and chaff, while the frictional contact with the rough surfaces thoroughly scours the grain. All rubbish contained in the grain is caught by the plates E and is readily removed. By reason of the ready access of air to the spout the grain is also thoroughly cooled in passing therethrough. To further expel dust and chaff, a blower or suction-fan may be provided to produce a strong blast of air through the spout, such blower or suction-fan being connected with said spout in any suitable manner. In order to prevent any grain from passing through said spout without being thoroughly scoured, screens G of small mesh may be alternated with the plates D, such screens extending from the top wall of the spout to about the middle thereof and set at an opposite incline to the plates D, as indicated in dotted lines in Figs. 1 and 2. The scouring action may be further increased by corrugating the side walls of the spout, as shown in Fig. 5, or providing short inclined screens H extending inwardly from said side walls, as shown in Fig. 4.

My said device is very efficient in its operation and is exceedingly economical, inasmuch as it requires no power or labor, as do the grain-cleaning machines generally in use.

I claim as my invention—

1. A grain-spout having walls of wire-cloth, a plurality of downwardly-inclined screens of wire-cloth interposed in said spout at intervals and extending from the lower wall of same to a point adjacent the middle of the spout, and downwardly-inclined screens of large mesh interposed between the lower ends of said first-named screens and the upper 40 wall of the spout, substantially as described.
2. A grain-spout having walls of wire-cloth, a plurality of downwardly-inclined screens of wire-cloth interposed in said spout at intervals and extending from the lower wall of same to a point adjacent the middle of the spout, and screens of large mesh interposed between the lower ends of said first-named screens and the opposite wall of the spout, and doors in said last-named wall above each 45 of said last-named screens, substantially as described.
3. A grain-spout having walls of wire-cloth, inclined slots in the side walls thereof, and screens interposed and supported in said 50 slots and extending from the upper to the lower wall of same, the upper portion of said screens being of a mesh fine enough to prevent the passage of the grain therethrough and the lower portion of same being of a mesh 55 large enough to permit the passage of the grain but not the straw and other rubbish contained in the grain, substantially as described.
4. A grain-spout having walls of wire-cloth, inclined slots in the side walls thereof, and screens interposed and supported in said 60 slots and extending from the upper to the

lower walls thereof, the upper portion of said screens being of a mesh fine enough to prevent the passage of the grain therethrough 40 and the lower portion of same being of a mesh large enough to permit the passage of the grain but not the straw and other rubbish contained in the grain, substantially as described, and doors in one wall of said spout 45 adjacent said screen.

5. A grain-spout having walls of wire-cloth, the side walls of said spout being corrugated, inclined screens of wire-cloth interposed in said spout of a mesh fine enough to prevent 50 the grain passing therethrough and each extending from one wall thereof to a point adjacent the middle of said spout, and devices in said spout adapted to catch straw and other rubbish without hindering the passage of the 55 grain.

6. A grain-spout having walls of wire-cloth of a mesh smaller than the grain, downwardly-inclined screens of similar mesh interposed in said spout and each extending from the 60 lower wall thereof downwardly to a point adjacent the upper wall, and screens of a mesh coarse enough to permit the passage of the grain, interposed in the passages between the last-named wall and the lower ends of said 65 screens adapted to catch and retain straw and other rubbish contained in said grain.

In testimony whereof I affix my signature in presence of two witnesses.

FRANK W. HESS.
